SHIRT COLLAR

Frank Di Iuglio, New Haven, Conn.

Application August 10, 1936. Serial No. 95,071

3 Claims. (Cl. 2--131)

This invention relates to collars, and more particularly to a stiff or semi-stiff collar, which may either be attached to a shirt or separate from the shirt.

It is well known that collars of this character do not always hold their shape, and in some instances allow the tie to slip through the collar only with difficulty. Moreover, some difficulty is encountered in laundering such collars in view of the fact that the fold line is not always clearly defined, so that it sometimes occurs that when the collar is laundered it is not folded evenly, and therefore presents an unattractive appearance. By the present invention it is contemplated to provide a collar which will overcome the disadvantages referred to above in that the fold line will be clearly marked, so that the collar will always be folded and laundered in the proper shape, while at the same time the neckband and turnover portions of the collar will be in such relation to each other that the tie will slip readily therethrough. Moreover, the improved collar will, on account of its construction, maintain its proper shape and will always be worn comfortably by the wearer.

One object of my invention is the provision of an improved collar of the type described, which will be comfortable to the wearer and at the same time have the fold line clearly defined.

Another object of the invention is the provision of an improved collar of the character described wherein the foldover portion of the collar will be stiff or semi-stiff, and the neckband portion of the collar will be soft and comfortable to the wearer.

A still further object of the invention is the provision of a turndown collar of such character that the turndown portion will be spaced from the neckband portion so as to provide for the easy slipping of the tie through the collar, and which at the same time will have the other advantages set forth herein.

To these and other ends the invention consists in the novel features and combinations of parts to be hereinafter described and claimed.

In the accompanying drawing:

Fig. 1 is an elevational view of a completed collar embodying my invention;

Fig. 2 is a back view of the inner lining member of the collar;

Fig. 3 is a sectional view of the completed collar on line 3-3 of Fig. 1;

Figs. 4 and 5 are sectional views of the inner lining member of the collar taken respectively on lines 4-4 and 5-5 of Fig. 2; and

Fig. 6 is a sectional view similar to Fig. 3 but showing the collar turned down in the position in which it is worn.

As shown in Fig. 1, the collar consists, as is usual in collars of this character, of a neckband portion 10 and a turnover or turndown portion 11. While the collar is shown separately, it is understood that it may be attached to a shirt to be used as an attached collar. As shown in Fig. 3, the collar comprises two outer plies 12 and 13, which will preferably be continuous strips of material, the ply 13 being the front and the ply 12 the back ply.

Between these plies is the inner lining member shown in Fig. 2. This member comprises an upper turnover portion 14 of a relatively heavy and closely woven material, and a lower neckband portion 15 of a relatively light, loosely woven material. The upper portion 14 is provided with an adhesive substance of a suitable character so that, when properly treated, it will adhere or be fused to the front and back plies 12 and 13 throughout the turnover portion of the collar so that this portion of the collar will be relatively stiff. The neckband portion 15 of the inner lining member is, as stated, of relatively light, loosely woven material, and preferably will not be treated with a fusible material, so that it will not be fused to the plies 12 and 13, and the collar throughout the neckband portion will be relatively soft.

The meeting edges of the members 14 and 15 are placed in superposition and stitched along the line 16, shown in Fig. 2, so that there is a double edge below the line of stitching which overlies the upper portion of the neckband member 15. In other words, adjacent the upper edge of the neckband member, the lining member will be of three-ply thickness immediately below the line of stitching 16. A strip of material 17 is then stitched to the inner lining member as at 16a in such position that its upper edge substantially coincides with the upper folded edge of the neckband portion 15, which is substantially at the position of the line of stitching 16. The upper edge of this strip 17, when the lining member is constructed in this manner, determines the fold line of the collar in conjunction with the doubled over portion of the neckband 15 and the overlapping edge of the turnover portion 14. The upper edge of this strip 17, when the lining member is constructed in this manner, determines the fold line of the collar in conjunction with the doubled over portion of the neckband 15 and the overlapping edge of the turnover portion 14. In other words, over that area of the lining member covered by the strip 17, this member will be of four-ply thickness. The strip 17 is a single unfolded strip of relatively heavy and stiff material, and may be stitched in place at the same

time that the members 14 and 15 are stitched together, that is, all of the members 14, 15 and 17 may be secured together by the single line of stitching 16^a. In this case, such a line of stitching will be disposed as closely as possible to the upper edge of the strip 17.

In Fig. 4 of the drawing is shown the inner lining member in sectional view before the strip 17 has been applied. After the strip 17 has been applied, the appearance of the inner lining member is shown in Fig. 5.

After the inner lining member has been constructed as shown in Fig. 5, the back and front plies 12 and 13 of the collar are placed upon opposite sides of the lining member, and may be secured thereto by the stitching 16^b, 18 and 19 shown in Fig. 3. The upper or turnover portion of the collar may then be fused by the usual operation to cause the plies throughout this portion of the collar to adhere to the inner lining, which will provide for a certain amount of rigidity and stiffness in this portion of the article.

It will be apparent from Figs. 3 and 6 that the overlapping portions of the members 14 and 15, as well as the strip 17, are disposed upon the back side of the collar, or what may be termed the inside when the collar is folded as shown in Fig. 6. This provides a relatively smooth outer surface upon the "right" side of the collar, and also provides for the spacing of the turnover portion of the collar from the neckband portion thereof, as shown in Fig. 6, so that the tie will slip readily therethrough.

It will be obvious that the present collar combines a great many advantageous features. The fold line will be clearly defined by a thickening of the inner lining member at this point. Moreover, a part of the material for effecting this result is obtained by the overlapping edges of the members 14 and 15 below the stitch line 16, so that it is only necessary to apply thereto a single strip of material 17. In addition, when the added thickness is arranged upon the back or the inside of the collar, the turndown portion will be spaced from the neckband portion, as shown in Fig. 6, to provide for the free slipping of the tie therethrough, and at the same time the neckband portion will always be relatively soft and comfortable to the wearer, while the turnover portion will be relatively stiff so as to maintain its form and shape.

In the manufacture of such a collar it is desirable, as stated, to provide the members 14 and 15 of different weight and texture, so that the inner lining member consists of two separate members joined together instead of a single strip of material. Advantage is taken of this fact by the employment of the seam edges or overlapping edges of these two members to thicken the collar at the upper edge of the neckband portion, and, in cooperation with the strip 17, to

define the fold line of the completed article. It will also be seen that, as the strip 17 is stitched to the inner lining member above the folded seam edges of the parts 14 and 15, this strip, being of relatively heavy stiff material, will serve to hold these edges flatly against the neckband portion 15 so as to obviate any likelihood of these edges being doubled or rolled during the manufacture or laundering of the collar, and thus maintain it in smooth flat condition.

While I have shown and described a preferred embodiment of my invention, it will be understood that it is not to be limited to all of the details shown, but is capable of modification and variation within the spirit of the invention and within the scope of the appended claims.

What I claim is:

1. A foldover collar having front and back sections each comprising a single strip of material, and an inner lining member, said member comprising separate neckband and foldover sections having their meeting edges superposed and being stitched together along a line spaced slightly from said superposed edges, and said edge portions below said line of stitching being folded downwardly over the upper portion of the neckband section, a narrow single-ply strip of relatively heavy material being stitched to said member in a position overlying said folded edge portion at the rear side thereof whereby said inner lining member is of four-ply thickness at the upper edge of the neckband portion to define clearly the fold line of the collar and space apart the neckband and turnover portions of the completed folded collar.

2. A collar as in claim 1 wherein the foldover section of the inner lining member is of heavier material than the neckband section of said member, and wherein the collar is fused throughout the foldover portion only.

3. A fold-over collar having outer front and back sections each comprising a single strip of material, and an inner lining member, said member comprising separate neck band and fold-over sections, the neck band section having its upper edge doubled upon itself and secured adjacent its folded edge to one of said outer sections, and the fold-over section of said lining member having its lower edge overlapping the folded portion of said neck band section and secured thereto, and a narrow strip of relatively heavy material secured to said lining member to extend along the overlapping edges of the sections thereof and increase the thickness of the lining member, whereby said lining member is of four-ply thickness between the front and back sections at the upper edge of the neck band portion to define clearly the fold line of the collar and space apart the neck band and fold-over portions of the completed collar.

FRANK DI IUGLIO.
